UNITED STATES PATENT OFFICE.

SUTTON STRONG, OF TERRE HAUTE, INDIANA, ASSIGNOR TO THE STRONG CONCRETE PRODUCTS COMPANY, OF TERRE HAUTE, INDIANA, A CORPORATION OF INDIANA.

BUILDING-BLOCK AND WALL CONSTRUCTED THEREOF.

No. 920,212.

Specification of Letters Patent.

Patented May 4, 1909.

Application filed February 10, 1908. Serial No. 415,268.

To all whom it may concern:

Be it known that I, SUTTON STRONG, citizen of the United States, residing at Terre Haute, in the county of Vigo and State of Indiana, have invented certain new and useful Improvements in Building-Blocks and Walls Constructed Thereof, of which the following is a specification.

My invention relates to building blocks and to walls constructed thereof, and particularly contemplates the provision of a novelly constructed block which is adapted to the construction of walls of the interlocked spaced block type, and in which a better circulation of air is effected without impairing the strength of the blocks or the wall.

My invention further and specifically resides in the following features of construction and arrangement to be hereinafter described with reference to the accompanying drawings forming a part of this specification, in which like numerals are used to designate like parts throughout the several figures and in which,

Figure 1 is a side elevation of a portion of a wall under construction according to my invention, and with my improved blocks. Fig. 2 is a perspective view of the same. Fig. 3 is a perspective view of the bonding tie. Fig. 4 is a perspective view of one of my improved wall blocks. Fig. 5 is a similar view of one of the spacing blocks. Fig. 6 is a plan view of a portion of the wall of more than one thickness, and Fig. 7 is a sectional perspective view through a portion of the wall illustrating the construction, and the vertical and horizontal air passages thereof.

In the practical embodiment of my invention, I provide a plurality of wall blocks 5, adapted to be laid in spaced parallel lines upon their longitudinal edges and having their flat faces 6 extending outwardly, and their opposite faces 7 provided with longitudinal inwardly extending shoulders 8 facing the similar shoulders of the blocks of the opposite line, adapted to contact with spacing members inserted between the parallel lines or blocks, to afford longitudinal passage of air between the blocks and said spacing members, as shown at 9 in Fig. 1. The wall blocks 5 are further provided with a relatively deep recess 10 extending continuously therearound and approximately

centrally of its edges, and adapted to align with the similar recesses of the adjacent blocks to provide for the reception and retention of an opening or reinforcing agent. Said blocks are further provided centrally of their length and through each of the shoulders 8 with a transverse short recess 11 communicating with the recess 10, and providing for the reception and retention of a reinforcing agent spanning the parallel lines of blocks. Extending upwardly between the parallel lines of building blocks 5, and contacting the longitudinal shoulders 8, with the sides thereof, are spacing blocks 12, having centrally longitudinal recesses 13 cut in their ends, and laid end upon end to register their said recesses 13.

The spacing blocks 12 are of such length, and so formed, as to break-joint with the building blocks 5, that is to say, on each level of the wall, the joints of alternate series of the blocks 12, align with the joints of the blocks 5. When so aligned, a binding tie 14, having angularly bent ends 15, is adapted to be inserted within, and extending through the aligned recesses 13, in the ends of the spacing blocks 12, and through the transverse recesses 11, in the longitudinal shoulders 8 of the building blocks 5, in which position the angular headed ends 15 of said members 14 will extend within the continuous recess 10 of the building blocks 5 on each side of said recess 11, and will be held therein by the binding agent inserted within said recess 10, between the adjacent building blocks 5.

Thus it will be seen that I provide a simple and inexpensive form of building block which may be readily employed in the construction of an approved form of wall, in such manner that vertical and horizontal passage of the air is effected without in any way impairing the strength of the blocks or of the wall, and whereby the blocks forming the wall may be strongly bound together.

Having described my invention, I claim:

In a wall of the character described, the combination of inner and outer spaced parallel lines of building blocks, each of said blocks being provided with shoulders formed upon their inner faces along their upper and lower longitudinal edges, and extending toward one another, separate spacing blocks extending upwardly between said parallel lines of blocks, centrally of, and at

the ends of each of said blocks, and abutting only the said shoulders of said blocks, said spacing blocks being arranged in two series each breaking joint with the longitudinal edges of alternate tiers of said blocks, and having recesses in their abutting ends extending transversely of the wall, said building blocks having continuous recesses extending centrally along and within the edged faces thereof, and having recesses extending centrally and transversely of the said shoulders and formed in the outer surfaces thereof to communicate with said continuous recesses, and bonding ties extending through said transverse recesses of said shoulders and through the alining ends of

alternate ones of said spacing blocks, and having angular ends for engagement within said continuous recesses whereby the said spacing blocks abut only the said shoulders 20 of the said building blocks to allow for the vertical and horizontal passage of air there-between and to prevent the passage of moisture to the inner line of building blocks, substantially as described.

25

In testimony whereof I affix my signature in presence of two witnesses.

SUTTON STRONG.
